Primary Examiner — Mojtaba Tehrani(74) *Attorney, Agent, or Firm* — Thomas Horstemeyer, LLP(57) **CLAIM**

The ornamental design for a sight, as shown and described.

DESCRIPTION

FIG. 1 is a perspective view of a sight showing my new design;

FIG. 2 is a front view thereof;

FIG. 3 is a rear view thereof, from an end opposite that of FIG. 2;

FIG. 4 is a side view thereof;

FIG. 5 is a side view thereof, from a side opposite that of FIG. 4;

FIG. 6 is a top view thereof; and,

FIG. 7 is a bottom view thereof.

The broken lines depict portions of the sight that form no part of the claimed design.

1 Claim, 7 Drawing Sheets(56)
